PAGE 2

FIG. 2

FIG. 3

FIG. 4

FIGURE 1 is a perspective view of a service stand for elevated constructions embodying my design as seen from a high angle, showing its associated adjustable platform in a raised position;

FIGURE 2 is a perspective view thereof as seen from a low angle, showing the adjustable platform of the service stand in a lowered position;

FIGURE 3 is a top plan view of the service stand showing the adjustable platform extended horizontally; and

FIGURE 4 is a side elevational view of the service stand showing the adjustable platform extended horizontally.

The dominant features of my design reside in the portions of the service stand shown in full lines in the drawings.

I claim:
The ornamental design for a service stand for elevated constructions, substantially as shown and described.
